DRAPEY CORNICE DUST BOARD
MOUNTING

Hyman Jay Ault, Pasadena, Calif.

Application May 3, 1949, Serial No. 91,174

3 Claims. (Cl. 160—19)

1

The invention relates to drapery boxes or the like adapted to be installed above inwardly opening closure members for door or window openings to support draperies and the like without interfering with the act of opening or closing of the door or window closures.

It is an object of the invention to provide means for mounting a dust box or the like to permit the box to have swinging movement with a closure member so that the drapes suspended from the box will offer no obstruction to the opening or closing movement of the closure member.

An additional object of the invention is to provide supporting hardware for a drapery box or the like adapted to vary selectively the distance between the dust board of the box or the like and the top of the door as well as the distance the box may be disposed in advance of the door.

The invention consists in the details of construction and in the combination and arrangement of the several parts of my improved drapery box whereby certain advantages are attained, as will be hereinafter more fully set forth.

In order that my invention may be better understood, I will now proceed to describe the same with reference to the accompanying drawings, wherein:

Figure 1 is a view in perspective of a box structure embodying the invention, the valance of the box being omitted;

Figure 2 is a view similar to Figure 1, but showing the door in an open adjustment;

Figure 3 is a view similar to Figure 2, but with a side wall in close proximity to the hinged side of the door;

Figure 4 is an enlarged fragmentary sectional view illustrating in detail certain of the hardware herein comprised;

Figure 5 is a sectional view taken substantially on the line 5—5 of Figure 4;

Figure 6 is a view in perspective of the hinge hardware herein embodied, a second position of certain of the parts being indicated by broken lines.

The mounting for the cornice dust board as herein embodied comprises an angled bracket of inverted L-form having its vertical flange portion 10 provided with several apertures for its securement, by screws 11, to the frame 12, of a door or casement window, or to the wall adjacent the frame, and a second elongated angled bracket member, also of inverted L-form, which has one of the end edges of its vertical flange portion 15

connected with the outer side edge of the vertical flange portion 10, of the first angled bracket, by a hinge formation 16, with its horizontal flange portion 17 partially overlying the horizontal flange portion 18, of the first angled bracket. The horizontal flange portion 17, of the second angle bracket, is provided with several apertures which, with the exception of the one that is in that portion of the same overlying the horizontal flange portion 18, of the first angle bracket, are for its securement, by screws 19, to one end of the lower side of the dust board 21, the said one aperture being adapted to be registered with an aperture in the horizontal flange portion 18 to receive a screw element 20, when it is desired to prevent movement of the second angled bracket relative to the first angled bracket. Still another angled bracket element, also of inverted L-form, has its horizontal flange portion *a* apertured for its securement, by means of screws *a'* (Figure 3), along the outer side edge of the lower side of the dust board 21, and the edge of the outer end of its vertical flange portion hingedly connected, as at 23, to the outer end edge of the vertical flange portion 15, of the second angled bracket, as best shown in Figure 6. Thus, by releasing the screw 20 from its engagement with the said one aperture in the horizontal flange portion 17, of the second angled bracket, the latter bracket will be free to swing laterally on the hinge 16 correspondingly with the opening and closing movements of the closure 13 of the wall opening, as will be later explained.

The other or free end portion of the dust board 21 is supported by an adjustable bracket construction C comprising a lower angular element 24 firmly secured to the upper part of the closure member 13 adjacent to its outer or freely swinging edge so that one of the legs *b* of said lower angular element extends inwardly from the door and has a slot 25 disposed lengthwise thereof. An intermediate angular bracket element 26 is provided in one of its legs *d* with a longitudinally disposed slot 27 and in its other perpendicularly related leg *e* with a plurality of holes 28 spaced apart lengthwise thereof. The leg *e* is adjustably secured to the lower angular element 24 by means of a bolt 29 extending through the slots 25 and 27 in the elements 24 and 26 respectively. The intermediate element 26 is arranged with its leg *e* upwardly disposed.

The top member 30 comprises the perpendicularly related legs *f* and *g*, the depending leg *f* being provided therealong with the spaced openings 28 for selected register with one of the

openings 28' spaced along the leg e of the member 26 and through which registering opening is inserted a bolt 31 or the like. A track 32 is secured to the undersurface of the dust board 21 at the end portion thereof remote from bracket member 22 and extending lengthwise of the dust board.

Extending into the track 32 through the slot 33 thereof is a shank 34 of a heavy duty bolt, the head 34' of which freely slides within the track 32. The shank 34 is freely disposed through the leg g and threading on the shank 34 above and below the leg g are the lock nuts 35 which coact with the leg g to hold the leg g in its selected adjustment lengthwise of the shank 34.

When the plate 17 is secured by the screw 20 to the horizontal leg portion 18, of the first angled bracket, as shown in Figure 3, so that the hinge 16 is inoperative, the board 21 will swing on the hinge 23 when the closure member 13 is opened or closed.

The bracket construction C provides means whereby the position of the dust board 21 with respect to the door 13 may be selectively adjusted in a horizontal direction within certain limitation while the relative adjustment of the elements 26 and 30 permits a vertical adjustment of the dust board 21 and which vertical adjustment may be further obtained through the medium of the bolt 34 and lock nuts 35.

In the operation of the device, when the closure member such as the door 13, is opened, the dust board 21 will be pushed inwardly by reason of the connection of the bracket structure between the door and the dust board and since the end of the dust board nearest to the hinge mounting for the door, is pivotally mounted to one side of the axis of the door hinges, it will be apparent that the dust board will not swing on the same axis of the door and accordingly it will have some slight longitudinal movement as well as its swinging movement on the hinge 16 or the two hinges 16 and 23, when mounted as shown in Figure 3. Accordingly the sliding coupling between the upper member 30 of the bracket and the track 32 is provided and is essential for such compound movement.

From the foregoing description it is thought to be obvious that drapery boxes or the like constructed in accordance with my invention are particularly well adapted for use by reason of the convenience and facility with which they may be assembled and operated.

I claim:

1. In combination, a closure for a wall opening of a building, the closure being hinged to swing inwardly on vertical hinge pins and a

drapery cornice dust board mounting for the opening, said mounting comprising a bracket secured to the wall adjacent the hinged side of the closure, a second bracket secured transversely of one end of the lower side of said dust board, hinge means connecting the inner end of said second bracket to the outer side of the first bracket, a third bracket secured along the outer side edge of the lower side of said dust board adjacent the said one end thereof, pivot means connecting the outer end of said third bracket to the outer end of said second bracket, a fourth bracket mounted on said closure adjacent the unhinged side thereof, and a slidable connection between the fourth bracket and the adjacent end of the lower side of said dust board.

2. The invention as defined in claim 1, with the first, second and third brackets each being of inverted L-form and each having a horizontal flange and a vertical flange, the horizontal flanges of the second and third brackets being secured to the lower side of said dust board and the horizontal flange of the first bracket underlying the inner end portion of the horizontal flange portion of the second bracket, the horizontal flange portions of said first and second brackets having a pair of aligned apertures, and a screw normally engaged in said apertures to hold the second bracket against swinging movements relatively to the first bracket and adapted to be released from its engagement with the aperture in the second bracket to allow the latter to swing on the hinge connection between the same and the first bracket correspondingly with the opening and closing movements of the said closure.

3. The invention as defined in claim 1, wherein the said slidable connection comprises a longitudinally disposed channel element and a headed element carried by the fourth bracket and having its headed end engaged in the channel of said element.

HYMAN JAY AULT.
